STRIPPABLE DISPENSING SHEATH AND METHODS FOR APPLYING THE SAME TO ARTICLES OF MERCHANDISE

Sidney V. Winton, New York, N.Y., assignor, by mesne assignments, to Lionel Timfow, North Caldwell, N.J.

Filed Dec. 5, 1962, Ser. No. 242,502

9 Claims. (Cl. 206—47)

My invention relates to merchandising containers generally and specifically to a strippable dispensing sheath and methods for applying the same to articles of merchandise.

In the hardware and home supply retail industry, it is frequently necessary to both display and dispense a wide variety of articles of merchandise having various shapes and sizes, for instance, metal strips, moldings, door saddles, rods, sheets, blades, tubes, pipes and the like.

These articles of merchandise are, within each particular class, of the same general shape but vary in size. In the past, it has been necessary to either place these items in individual containers such as boxes or to assemble them in tied bundles according to sizes. Recently, the packaging industry has employed a loose-fitting plastic sleeve or bag. The expedient of the box is not only expensive but requires an extremely large floor area for storage and display. If an individual container such as a box is not employed, the articles must be bundled together or loosely stacked and are frequently damaged or misplaced. The sleeve or bag is, on the other hand, unsightly and easily torn. It is desirable that such articles of merchandise be both displayed and dispensed individually. The efficient manner of doing so is to hang them on hooks secured to a peg board so that they may be both seen and dispensed individually. In addition, individually sheathed items may be placed in a floor rack or stored, which provides for both display and dispensing.

Therefore, it is among the objects and advantages of my invention to provide a strippable dispensing sheath for articles of merchandise which is applied directly to the article of merchandise as a liquid coating, quickly solidifying thereon forming an airtight, hermetic contour sheath.

Another object of my invention is to provide a strippable dispensing sheath for articles of merchandise which is transparent and easily stripped therefrom.

Yet another object of my invention is to provide a strippable dispensing sheath for articles of merchandise which is provided with an integral tear strip partially embedded in the sheath and adapted to rupture and facilitate stripping of the same.

Yet another object of my invention is to provide a strippable dispensing sheath which is provided with a tear strip which projects beyond the article of merchandise and may be provided with means for attaching the same to a peg board or the like.

Still another object of my invention is to provide a strippable dispensing sheath for articles of merchandise which may integrally embody a transparent protective container for auxiliary parts related to the articles of merchandise such as screws, bolts, nuts and the like.

Yet a further object of my invention is to provide a strippable dispensing sheath for articles of merchandise which is less costly and more durable than other containers.

Another object of my invention is to provide methods for applying a strippable dispensing sheath to articles of merchandise employing a combination tear strip and supporting member which may be secured directly to the article of merchandise by means of a pressure sensitive adhesive, the said strip adapted to support the article of merchandise as a liquid plastic coating is applied thereto.

2

Still another object of my invention is to provide methods for applying a strippable dispensing sheath to articles of merchandise in which auxiliary equipment such as nuts, bolts and the like are first sealed within a transparent plastic container and affixed to the article of merchandise by means of a pressure sensitive adhesive prior to the application of a liquid plastic coating adapted to overlie both the merchandise and the container secured thereto.

Yet a further object of my invention is to provide methods for applying a strippable dispensing sheath to articles of merchandise in which auxiliary equipment such as screws, nuts and bolts are seated within contour recesses in a thin plastic sheet and the sheet covered with a transparent plastic member having a pressure sensitive adhesive on both sides, the container being secured to the article of merchandise prior to the application of an overlying coat of liquid plastic which dries to form a hermetically sealed, contour sheath.

These objects and advantages as well as other objects and advantages may be achieved by my invention embodiments of which are illustrated in the drawings in which:

FIGURE 1 is a side elevational view of a portion of an article of merchandise showing a tear strip fixed thereto and a transparent, strippable dispensing sheath applied over the tear strip and the article of merchandise.

FIGURE 2 is a side elevational cross-sectional view taken along line 2—2 in FIGURE 1.

FIGURE 3 is a side elevation view of the conveyor system for coating and drying the suspended articles.

FIGURE 4 is a view in perspective of an elongated, thin transparent plastic sheet having indentations therein to accommodate auxiliary equipment.

FIGURE 5 is a view in perspective of a carrier showing articles of merchandise suspended therefrom.

FIGURE 6 is a rear elevational view of the tear strip shown in FIGURE 1.

FIGURE 7 is a side elevational cross-sectional view of a transparent container for auxiliary equipment such as screws, nuts, bolts, and the like.

Referring now to the drawings in detail, my invention comprises an elongated tear strip 11 which is affixed directly to an article of merchandise 12. The tear strip 11 may be die cut from a flat sheet of heavy paper, cardboard, plastic or the like and comprises a detachable support end 13 formed integrally with an enlarged portion 14 separated therefrom by a pair of opposed indentations 15, 15. The indentations 15, 15 facilitate detaching the removable end 13 from the enlarged portion 14. Formed integrally with the enlarged portion 14 on the opposite side thereof is an elongated tail 16. A hole 17 may be punched through the center of the enlarged portion 14. The rear face of the tear strip 11 may be coated with a suitable pressure sensitive adhesive 18. The front face 19 may be provided with printed instructions or advertising material.

It is frequently necessary to merchandise auxiliary equipment such as screws, bolts, nuts and the like with each individual article sold. It is most convenient to secure these screws, nuts, bolts and the like directly to the part with which they are to be used in the manner shown in FIGURES 2 and 3. In FIGURE 4, an elongated sheet of transparent plastic 20 is shown having a plurality of depressions 21 in the shape of a screw or bolt. The depressions 21 may be formed by any suitable die either when the plastic strip is fabricated or thereafter by the application of heat and pressure. The screw or bolt 22 may be seated within the depression 21 in a manner to be hereinafter described. A transparent plastic cover sheet 23 having a pressure sensitive adhesive coating 24 applied thereto is applied to the transparent sheet 20 overlying the depressions 21 sealing the screws 22 therein. The opposite side of the cover sheet 23 is also pro-

60
65
70

vided with a pressure sensitive adhesive coating 25 to facilitate affixing the sheet with screws sealed therein to the article of merchandise 12.

The elongated sheet 20 may also be provided with perforations 26 to facilitate detaching individual units or combinations thereof which contain the precise number and type of screws for the particular article of merchandise 12.

My method of applying the strippable dispensing sheath to the article of merchandise comprises affixing the tear strip 11 to the article of merchandise 12 by means of the pressure sensitive adhesive 18 on its rear face.

The elongated transparent plastic strip 20 is then passed over a vibrating table and the screws, nuts, bolts or the like spread thereon. The vibrating table will cause the screws 22 to drop into the depressions 21 as the sheet 20 is passed over the vibrating table.

The transparent covering sheet 23 having the pressure sensitive adhesive 24 applied thereto is affixed to the face of the elongated sheet 20 overlying the depressions 21 and screws 22 thereby sealing the screws 22 within the depressions 21. The top most layer of pressure sensitive adhesive 25 on the cover sheet 23 may be provided with an appropriate strippable protective paper and the assemblage rolled and shipped to the point of application of the transparent plastic sheath. Prior to application of the liquid plastic to the merchandise, the sheet 20 is separated along the perforated lines 26 or in the alternative, die stamped at appropriate lengths to cut off segments having the proper number of screws 22. Of course, the sheet 20 may otherwise be cut in any appropriate manner. The pressure sensitive protective paper may then be stripped off the top most pressure sensitive adhesive layer 25 and the container pressed preferably against the rear face of the article of merchandise 12 in the general proximity of the tear strip 11.

The articles of merchandise 12 are then secured to a rack 27 by means of resilient clips 28 which fasten to the support end 13 of the tear strip 11. The rack 27 is attached to a pulley lift 29 which is in turn secured to a horizontal conveyor belt 30. In FIGURE 3, the articles of merchandise 12 have been fastened to the rack 27 in the left most portion. Thereafter, the lift 29 pulls the rack 27 with the merchandise 12 attached thereto upwardly through the opening 31 in the ceiling 32 and the conveyor 30 then carries it to the right to a position immediately above a second opening 33. Beneath the second opening 33, there is a vat 34 of a suitable liquid plastic 35. A number of plastics may be employed, such as vinyl chloride, a bursterate, or the like. In addition, while I have shown the process to be one of dipping in a vat of the liquid plastic, it should be understood that the plastic may be sprayed thereon or applied in any other well-known suitable manner.

The lift 29 thereupon descends lowering the rack 27 so that the articles of merchandise are immersed in the liquid plastic 35 in the vat 34, the top most surface 36 of the liquid plastic 35 extending upwardly over the enlarged portion 14 of the tear strip 11 and partially upon the support end 13 thereof. Preferably, the clamps 28 should not touch the plastic 35.

Thereupon, the lift 29 is raised again to withdraw the articles of merchandise 12 from the vat 34 and the conveyor 30 moves the rack 27 to the right to a drying area. As may be seen in FIGURE 2, the plastic 35 forms a transparent coating over the tear strip 11 and over the sheet 20 having depressions 21 therein containing the screws 22, thereby forming a hermetic sheath 37 which secures both the tear strip 11 and the screw container firmly to the article of merchandise 12. The liquid plastic 35 never touches the screws 22 and they are therefore ready to use immediately when removed from the container. In addition, since the clamp 28 engages only the top most support end 13 of the strip 11, there are no clamp marks or holder marks in the plastic sheath 37 on the merchandise 12 or the tear strip 11. After the plastic

35 has dried to form the coating or sheath 37, the support end 13 of the tear strip 11 may be cut or torn away from the enlarged portion 14 at the indentations 15. The plastic sheath 37 is very thin at the hole 17 and may be easily ruptured so that the article of merchandise 12 may be suspended from an appropriate hanger secured to a peg board of the like.

The foregoing description is merely intended to illustrate an embodiment of the invention. The component parts have been shown and described. They each may have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

What is claimed:

1. A strippable dispensing sheath for articles of merchandise comprising,

(a) a tear-strip detachably secured to an article of merchandise, a portion of the tear-strip extending beyond the edge of the article of merchandise,

(b) a sealed container receiving items complementary to the article of merchandise detachably secured to the said article, and

(c) a relatively thin, strippable contour sheath overlying the container, the article of merchandise and at least that portion of the tear-strip attached to the article of merchandise.

2. A strippable dispensing sheath for articles of merchandise comprising,

(a) a tear-strip detachably secured to an article of merchandise, a portion of the tear-strip extending beyond the edge of the article of merchandise,

(b) a first sheet having a pressure sensitive adhesive on both sides secured to said article of merchandise by means of the said pressure sensitive adhesive,

(c) a second sheet having a depression therein secured to the first sheet by means of the said pressure sensitive adhesive, said depression receiving an item complementary to the said article, the first and second sheets collectively defining a sealed container,

(d) a relatively, thin, strippable contour sheath overlying the article of merchandise, the container and that portion of the tear-strip attached to the article of merchandise, the said sheath securing the tear-strip and container to the article of merchandise.

3. A strippable dispensing sheath for articles of merchandise comprising:

(a) the structure in accordance with claim 1 in which:

(b) the strippable contour sheath extends on to at least

a portion of the tear-strip extending beyond the edge

of the said article.

4. A method for applying a strippable dispensing sheath to an article of merchandise comprising,

(a) securing a tear-strip to the article of merchandise by means of a pressure sensitive adhesive, a portion of the tear-strip extending beyond the edge of the article,

(b) freely suspending the article of merchandise from the end of the said portion of the tear-strip opposite the article,

(c) applying a relatively thin coating of a liquid plastic over the article of merchandise and tear-strip secured thereto while suspended, the coating extending over at least a part of the portion of the tear-strip extending beyond the edge of the article, and

(d) drying the coating to form a strippable, contour dispensing sheath.

5. A method for applying a strippable dispensing sheath comprising,

(a) the method in accordance with claim 4, and

(b) severing the portion of the tear-strip between the article and the furthest extension of the plastic sheath thereon.

6. A method for applying a strippable dispensing sheath to an article of merchandise comprising:
 (a) detachably securing a tear-strip to the article of merchandise, a portion of the tear-strip extending beyond the edge of the article,
 (b) freely suspending the article of merchandise from the end of the said portion of the tear-strip opposite the article,
 (c) applying a relatively thin coating of a liquid plastic over the article of merchandise, the coating extending over at least a part of the said portion of the tear-strip extending beyond the edge of the article,
 (d) drying the coating to form a strippable contour sheath.
7. A method for applying a strippable dispensing sheath to an article of merchandise comprising:
 (a) the method in accordance with claim 6, and
 (b) severing the portion of the tear-strip between the article and the furthest extension of the plastic sheath thereon.
8. A method for applying a strippable dispensing sheath to an article of merchandise comprising,
 (a) the method in accordance with claim 6, and
 (b) detachably securing a sealed container receiving items complementary to the article of merchandise to the article of merchandise before applying the said relatively thin coating of plastic such that said thin coating when applied extends over the said container, the article of merchandise and the tear-strip.
9. A method for applying a strippable dispensing sheath to an article of merchandise comprising:
 (a) securing a tear-strip to the article of merchandise by means of a pressure sensitive adhesive, a portion of the tear-strip extending beyond the edge of the article,

5

10

20

25

30

35

- (b) securing a first sheet having a pressure sensitive adhesive on both sides thereof to said article of merchandise by means of the said pressure sensitive adhesive,
 (c) applying a second sheet having a depression therein to the first sheet by means of the said pressure sensitive adhesive, said depression receiving an item complementary to said article of merchandise, the first and second sheets collectively defining a sealed container,
 (d) freely suspending the article of merchandise from the end of the said portion of the tear-strip opposite the article,
 (e) applying a relatively thin coating of liquid plastic over the article of merchandise, the container and the tear-strip secured thereto while suspended, the coating extending over at least a part of the portion of the tear-strip extending beyond the edge of the article, and
 (f) drying the coating to form a strippable contour dispensing sheath.
